WAVELENGTH MODULATION

Charles N. Kimball, Jackson Heights, N. Y., assignor to Radio Corporation of America, a corporation of Delaware

Application October 2, 1940, Serial No. 359,314

14 Claims. (Cl. 179—171.5)

This application concerns a method of and means for modulating the wave length of wave energy in accordance with signals. The particular means I have provided for modulating the wave length of wave energy is essentially a phase modulator. As will be seen by those skilled in the art once they understand my system, the same may also be used to produce frequency modulation of wave energy.

An object of my invention is to provide a new and improved wave length modulation system which is simple in nature, reliable in operation, and which requires a small amount of circuit elements and tubes to carry out the modulation process.

Another object of my invention is to attain the object set forth in the preceding paragraph and to, at the same time, provide a system wherein the wave length modulations are linear with respect to the amplitudes of the modulating potentials.

In its broadest aspect my system includes a discharge device having electrodes including a control electrode, a cathode, and an electron collecting electrode with the cathode raised above ground or equivalent alternating-current potential by a reactance. Voltages of carrier wave frequency are impressed across the grid-to-cathode tube space and the reactance in series. This causes alternating current to flow in this series circuit. The current flowing in the series circuit leads or lags the voltage in the series path depending on whether the reactance is capacitive or inductive. As a consequence, an alternating-current voltage which is displaced in phase relative to the original voltage developed across the series circuit is developed between the grid and cathode. By modulating the mutual conductance of the device the phase of the voltage appearing across the cathode reactance in the series circuit is varied. The voltage developed between the grid and cathode is correspondingly modulated in phase. This phase variation is linear with respect to variations in mutual conductance of the device and the latter are made linear with respect to modulation potential range.

Preferably, the carrier voltage worked with is of relatively low frequency, say, for example, 100 kilocycles. The modulated carrier is then frequency multiplied to the required extent, limited, if desired, amplified and used to convey the modulation potentials.

In describing my invention in detail, reference will be made to the attached drawings wherein:

Fig. 1 illustrates the essential elements of a 55

wave length modulation system arranged in accordance with my invention;

Figs. 2 and 3 are respectively a basic circuit used to show the manner in which the phase displaced voltages are developed in the tube of Fig. 1 and a vector diagram also used to show how the voltages developed in my novel system, one of which is of variable phase, cooperate to produce a resultant phase modulated output voltage;

Fig. 4 illustrates a modification of Fig. 1, while

Fig. 5 illustrates the manner in which a balanced modulation system, in accordance with my invention, is arranged.

A simplified circuit arrangement of my modulator is shown in Fig. 1. The basic circuit comprises a pentode 10 with a reactive load C_k in its cathode circuit. The load may be either inductive or capacitive, depending upon the desired direction of carrier phase shift. The basic circuit is drawn below.

Tube 10 is a pentode, with mutual conductance gm and plate resistance r_p so high that its plate alternating current i_p equals its mutual conductance, gm times its grid alternating excitation voltage E_{gk} .

As stated above, the object of the circuit is to cause the phase of the grid-to-cathode voltage E_{gk} to vary in accordance with the amplitude of the modulation voltage E_{mod} . This variation in phase acts to vary the phase of the plate current in the tube relative to its nominal unmodulated phase.

The tube 10 has its grid 12 excited by carrier wave voltage from source 8 through coupling condenser 9 and also by modulation voltage from source 6 through radio-frequency choke 7.

The diagram shows E_{mod} (an audio voltage) and $E_{carrier}$ (a radio-frequency voltage) applied to a common grid through appropriate chokes and filters, but other types of connection, i. e., multi-grid tubes, may be employed.

Neglecting the direct-current considerations, the basic circuit is as illustrated in Fig. 1 and in Fig. 2 which is a simplified circuit similar to 45 that of Fig. 1.

$$I_p = E_{gk} gm$$

(Basic action of the pentode.)

$$E_k = I_p Z_k$$

where Z_k is the impedance in the cathode load. (Impedance drop in Z_k .)

$$E_{gk} = E_{carrier} - E_k$$

(The cathode potential is subtracted from the potential impressed on the grid to get E_{gk} .)

From these three equations we get

$$E_{gk} = E \text{ carrier} \div (1 + Z_k g m)$$

In the figures

$$Z_k = \frac{1}{j \omega C_k}$$

therefore

$$E_{gk} = \frac{E \text{ carrier}}{\sqrt{1 + \frac{g m^2}{C_k^2 \omega^2}}}$$

and E_{gk} leads E carrier by

$$\tan^{-1} \frac{g m}{\omega C_k}$$

shown as ϕ in Fig. 3.

By varying the mutual conductance $g m$ the phase of E_{gk} is varied. In this manner modulation is accomplished. The phase modulated waves so produced are utilized for signalling purposes directly or after multiplication, amplification, and amplitude limiting.

If the cathode load had been an inductive reactance of $L_{k\omega}$, the value of E_{gk} would have been

$$E_{gk} = \frac{E \text{ carrier}}{\sqrt{1 + g m^2 \omega^2 L_{k\omega}}}$$

and the vector representing E_{gk} would lag that representing E carrier by $\phi = \tan^{-1} \omega L_{k\omega} g m$.

Considering the capacitance loading case, the vector diagram of Fig. 3 shows the action of E_{gk} is in the first quadrant with the vector E carrier as shown.

In these single-sided circuits (or in any phase modulator) it is essential that ϕ vary substantially linearly with the instantaneous value of E mod. Hence ϕ is restricted to values for which $\tan \phi = \phi$ within, say, 5%. Thus, 25° may be taken as top value for ϕ , for acceptable distortion. $\tan 25^\circ = .466$.

To examine the effect of a variation of $g m$ (due to E mod) on the amplitude of the plate current resulting from a shift in the phase of E_{gk} it is necessary merely to note that $I_p = g m E_{gk}$. Hence, where a capacitive reactance

$$\frac{1}{C_k}$$

is used

$$I_p = g m E_{gk} = \frac{g m E \text{ carrier}}{\sqrt{1 + \frac{g m^2}{C_k^2 \omega^2}}}$$

$$I_p = \frac{\left(\frac{g m}{\omega C_k}\right) E \text{ carrier} \omega C_k}{\sqrt{1 + \frac{g m^2}{C_k^2 \omega^2}}} = \frac{E \text{ carrier} \omega C_k \tan \phi}{\sqrt{1 + \tan^2 \phi}} \quad (A)$$

Thus, where $\phi = \tan \phi$ within 5% and ϕ is in radians Equation A may be approximated by the following equation

$$I_p = \frac{E \text{ carrier} C_k \phi}{\sqrt{1 + \phi^2}}$$

It is obvious that if angle ϕ is varied between 25° and 0° that the 0° point is attained only by reducing the mutual conductance $g m$ to zero, which results in zero alternating plate current I_p , hence the variation in angle ϕ must be restricted to a range resulting in acceptable amplitude modulation. Since E carrier and $C_k \omega$ are considered constant we need to examine the varia-

tion in I_p with ϕ at $\phi = 25^\circ$ or .436 radian, using exact Formula A.

At $\phi = 25^\circ$

$$I_p = E \text{ carrier} C_k \omega \quad (.436)$$

At $\phi = 10^\circ$

$$I_p = E \text{ carrier} C_k \omega \quad (.176)$$

Hence, if the initial unmodulated value of

$$\frac{g m}{C_k \omega}$$

were set so that the value of ϕ (for zero E mod) were approximately 17.5° the modulating voltage could be used to swing $g m$ above and below this value, to cause maximum phase shift of 25° and a minimum of 10° resulting in approximately 39% amplitude modulation, i. e.,

$$\frac{.436 + .176}{.436 + .176} \times 100 = 39\%$$

This amplitude modulation may be clipped off in a subsequent limiter stage.

The useful region of phase variation lies between the values shown above, unless one wishes to get about 5 more degrees phase modulation (i. e., a minimum value of $\phi = 5$ degrees) in which case the resultant amplitude modulation is greater.

A similar analysis can be made for the case of inductive cathode loading, and the results are the same if $L_{k\omega}$ is substituted for

$$\frac{1}{C_k \omega}$$

in the preceding development.

This is the basic scheme of the invention, i. e., to cause E_{gk} to vary its phase relation with respect to its unmodulated position. It can be shown to do so without substantial variation in amplitude. Due, however, to the dependence of the amplitude I_p (alternating current component) on the value of $g m$, as varied by E mod, the use of I_p in this phase variation tube restricts the value of phase shift obtainable by the system. Any reduction in I_p which can be attained will obviously reduce the undesired amplitude modulation and permit use of larger phase deviations.

Hence, to improve this situation, consider Fig. 1 modified as shown in Fig. 4, to which is added a second tube 20 having its grid 24 and cathode 26 coupled by tuned circuits 28 and 30 to the grid 12 and cathode 11 of tube 10.

A high impedance tuned circuit, resonant at the constant frequency of E carrier is connected between grid 12 and cathode 11 of the first tube 10. Its impedance is high compared to

$$\frac{1}{C_k \omega}$$

A tuned secondary 28 transfers the voltage E_{gk1} to the grid 24 of a second pentode tube 20.

Let K be the voltage gain of the tuned transformer 31 then I_{p2} (the alternating-current carrier frequency plate current of tube 20) = the mutual conductance of tube 20 $g m_2$ times the carrier voltage on the grid of tube 20 $E_{g2} = g m_2$ times a constant K times the voltage E_{gk1} between the grid and cathode of tube 10

$$I_{p2} = g m_2 K E_{g2} = \frac{g m_2 K E \text{ carrier}}{\sqrt{1 + \frac{g m_1^{-2}}{C_k^2 \omega^2}}}$$

Hence, the phase variation of I_{p2} is substantially equal to that of E_{gk} . Furthermore, the merit in this improved system lies in the fact that the amplitude of I_p (its alternating current component) in tube 20 is practically constant and independent of gm_1 , when the latter is varied in accordance with the applied modulation, even when gm_1 is reduced to zero.

Thus, in the latter case, if the tuned circuit 30 primary impedance

$$Z \text{ is } >> \frac{1}{C_k \omega}$$

$E_{gk} = E$ carrier when $gm_1 = 0$, and, when

$$\frac{gm}{C \omega_k} = .46$$

(for $\phi_c = 25^\circ$ phase deviation in E_{gk} from E carrier)

$$E_{gk} = \frac{E \text{ carrier}}{\sqrt{1 + .466^2}} = .91 E \text{ carrier}$$

an amplitude modulation of only 9%.

Thus, in the modification of Fig. 4, the first tube is used only to effect a phase change of the second tube's grid voltage. The plate current variations in the first tube are not used to supply any utilization circuit. Note that the full capabilities of the scheme are exploited by driving the first tube from zero bias (or even positive values of E_g) on the modulating grid to cut-off, to get maximum phase deviation.

As shown above, the system is essentially single-sided, but phase deviations on both sides of the quiescent unmodulated phase are obtainable by using push-pull tubes for the phase changers, one with a capacitor in the cathode and the other with an inductive cathode load. In Fig. 5, I have illustrated a circuit using tubes 40 and 60 to phase deviate the carrier about a medium phase. In Fig. 5, the second set of tubes 80 and 100 are connected in conventional pentode style.

In Fig. 5, the control grids 41 and 61 of tubes 40 and 60 respectively are coupled by blocking condenser 43 and resistance 45 to a source of carrier wave voltages 46 to be excited thereby substantially in phase. The cathode 47 of tube 40 is connected to ground by a condenser C_k the function of which is similar to the corresponding condensers in the prior figures. The cathode 67 of tube 60 is connected to ground by an inductance L_k whose function is similar to that of the condenser C_k . This ground connection includes a bias resistor 65 and a carrier wave bypass condenser BC. The grids 41 and 61 are connected in push-pull relation by the secondary winding of a transformer 66 the primary winding of which is connected to a source of modulating potential 6. A negative bias is supplied to the grids 41 and 61 by source 71. The remaining grids in the tubes 40 and 60 are connected as shown and the connections are believed self-explanatory. The direct-current circuit of cathode 47 comprises the radio-frequency choke and bias resistor 69 in series between the said cathode and ground. The grid 41 is connected by blocking condenser 70 to a tuned circuit 71 including an inductance which forms the primary winding of transformer 72. The secondary winding of this transformer is included in a tuned circuit 73 connected to the grid 81 of tube 80. A similar 70 blocking condenser 75, tuned circuits 76 and 77 of transformer 78 couples the grid 61 and cathode 67 to the grid 101 of the tube 100. The cathodes 83 and 103 of tubes 80 and 100 are connected to ground by biasing resistors 85 and 105. 75

These biasing resistances are shunted by radio-frequency bypass condensers BC. At this point it is noted that the screen electrodes of tubes 40 and 60 are also connected to the cathodes by bypass condensers BC. The anodes 87 and 107 of tubes 80 and 100 are tied together and connected to a tank circuit 108 from which the phase modulated voltages are derived.

The screen electrodes in tubes 80 and 100 are connected to positive potential sources. It is thought unnecessary to further describe this stage comprising tubes 80 and 100. The screen electrodes of tubes 40 and 60 are connected by resistances 49 and 79 to a positive potential source while the anodes of these tubes are likewise connected to a positive potential source.

The first pair of tubes are driven in push-pull by the modulation potentials from 6 and in parallel by carrier wave from 46.

$$L_k \omega = \frac{1}{C_k \omega}$$

at the input carrier frequency if the tubes 40 and 60 have similar mutual conductance characteristics gm . The tubes 40 and 60 are degenerative for modulation potentials (E mod), due to their bias resistors 65 and 69 being unbypassed for audio frequencies. The tubes 40 and 60 are so biased that the combined push-pull mutual conductance times grid modulation potential (gm vs E_g mod) characteristic is essentially linear over the operating range, i. e., each bias probably quite near cut-off.

The tube 40 causes its grid-to-cathode carrier voltage E_{gk} to lead its unmodulated phase position when its mutual conductance gm is increased. The tube 60 causes a phase lag in the carrier voltage of an equal amount during alternate half cycles of the modulating voltage wave.

40 The transformers 72 and 78 feeding the second pair of tubes 80 and 100 may be arranged for voltage step-up so that the grids of the tubes 80 and 100 are overloaded, to produce harmonic currents in the plate circuits thereof. These tubes may then be used for frequency or phase deviation multiplication. Of course, they may operate as amplifiers in which case multiplication may take place in latter stages. When used as amplifiers only, the tubes 80 and 100 are not overloaded. The tuned plate load 108 may be placed either between plates 87 and 107, or between the plates 87 and 107 in parallel and B+, depending upon the desired order of multiplication, i. e., even or odd order. When the plates 87 and 107 are connected in opposition by the winding of 108 direct current is supplied to a tap on the said winding.

60 Maximum phase deviation in either tube should be restricted to about 25° - 30° , i. e., approximately .45 radian for a frequency deviation of nKc (ultimate) the maximum phase deviation is

$$\phi_{\max} = \frac{\Delta f}{f} = \frac{nRc}{f}$$

65 radians where f is the audio frequency in kilocycles.

For a system with 30 cycles as the lowest tone and 100 kilocycle maximum deviation (200 kilocycle band)

$$\phi = \frac{100000}{30} = 3333 \text{ radians}$$

Thus, with this scheme, if about .5 radian deviation is produced in the modulating stage, an ultimate frequency multiplication of about 6600

is required. For narrow band systems this is reduced in proportion to the reduction in band width.

The necessary signal frequency multiplication may be accomplished by doubling or tripling several times in subsequent over-biased stages, etc. This is a familiar feature of all phase modulation systems.

If constant amplitude audio voltage is supplied to the modulator for all the audio frequencies involved, the output of the device is a phase modulated signal, i. e., the phase displacement of the carrier is independent of the audio frequencies employed. A frequency modulated signal with uniform frequency deviation for all audio frequencies is obtained by first applying to the modulator, an audio voltage whose amplitude varies inversely with audio frequency.

The source frequency, that is the frequency of carrier, will be in the vicinity of 100 to 300 kilocycles if the ultimate carrier frequency is approximately 40 megacycles. The exact value of the source frequency will depend upon the value of the carrier frequency employed and upon the required ultimate frequency deviation.

What is claimed is:

1. In a wave length modulator, an electron discharge device having electrodes including a grid and a cathode, a carrier frequency reactance in the cathode circuit of said device, means for developing a voltage of carrier wave frequency to be modulated across the impedance between said grid and cathode and said reactance in series whereby voltages of said frequency appear in said series circuit, and a phase displaced voltage of said frequency is developed between said grid and cathode, means for varying the mutual conductance of said device at signal frequency to thereby correspondingly vary the phase of said last voltage, and means for utilizing said last voltage.

2. In a wave length modulator, an electron discharge device having electrodes including a grid and a cathode, a capacitive carrier frequency reactance in the cathode circuit of said device, means for developing a voltage of carrier wave frequency to be modulated across the impedance between said grid and cathode and said reactance in series whereby voltages of said frequency appear in said series circuit, and a voltage of said frequency and of a phase which leads the phase of said first voltage is developed between said grid and cathode, means for varying the mutual conductance of said device at signal frequency to thereby correspondingly vary the phase of said last voltage, and means for utilizing said last voltage.

3. In a wave length modulator, an electron discharge device having electrodes including a grid and a cathode, a carrier frequency inductive reactance in the cathode circuit of said device, means for developing a voltage of carrier wave frequency to be modulated across the impedance between said grid and cathode and said reactance in series whereby voltages of said frequency appear in said series circuit, and a voltage of said frequency and of a phase which lags the phase of said first voltage is developed between said grid and cathode, means for varying the mutual conductance of said device at signal frequency to thereby correspondingly vary the phase of said last voltage, and means for utilizing said last voltage.

4. A modulator as recited in claim 1 wherein

said device is of the pentode type and of high plate resistance.

5. A modulator as recited in claim 2 wherein said device is of the pentode type having a high plate resistance.

6. A modulator as recited in claim 3 wherein said device is a pentode of high plate resistance.

7. In a wave length modulation system, an electron discharge device having electrodes including a grid and a cathode, a reactance in the cathode circuit of said device, means for developing a voltage of carrier wave frequency to be modulated across the impedance between said grid and cathode and said reactance in series whereby currents of said frequency flow in said series circuit and a phase displaced voltage of said frequency is developed between said grid and cathode, means for varying the mutual conductance of said device at signal frequency to thereby correspondingly vary the phase of said last voltage, a circuit tuned to the frequency of said last voltage coupled between said grid and cathode, and an output circuit coupled to said first named tuned circuit.

8. In a wave length modulation system, an electron discharge device having electrodes including a grid and a cathode, a reactance in the cathode circuit of said device, means for developing a voltage of carrier wave frequency to be modulated across the impedance between said grid and cathode and said reactance in series whereby currents of said frequency flow in said series circuit and a phase displaced voltage of said frequency is developed between said grid and cathode, means for varying the mutual conductance of said device at signal frequency to thereby correspondingly vary the phase of said last voltage, a circuit tuned to the frequency of said last voltage coupled between said grid and cathode, and an output circuit coupled to said first named tuned circuit.

9. In a wave length modulator, an electron discharge device of high internal impedance having electrodes including a grid and a cathode, a reactance in the cathode circuit of said device, means for developing a voltage of carrier wave frequency to be modulated across the impedance between said grid and cathode and said reactance in series whereby voltages of said frequency appear in said series circuit and a phase displaced voltage of said frequency is developed between said grid and cathode, means for varying the mutual conductance of said device at signal frequency to thereby correspondingly vary the phase of said last voltage, a circuit tuned to the frequency of said last voltage coupled between said grid and cathode, a circuit tuned to the frequency of said last voltage coupled to said first named tuned circuit, and a frequency multiplier coupled to said last named tuned circuit.

10. In a wave length modulation system, an electron discharge device of the pentode type having electrodes including a grid and a cathode, a reactance in the cathode circuit of said device, means for developing a voltage of carrier wave frequency to be modulated across the impedance between said grid and cathode and said reactance in series whereby currents of said frequency flow in said series circuit and a phase displaced voltage of said frequency is developed between said grid and cathode, means for vary-

ing the mutual conductance of said device at signal frequency to thereby correspondingly vary the phase of said last voltage, an electron discharge tube system of the pentode type having electrodes including a control grid, a cathode, and an output electrode, an output circuit coupled to the output electrodes of said tube, and means for applying voltages developed between said grid and cathode of said device to the grid and cathode of said tube of sufficient amplitude to overload said tube.

11. In a wave length modulation system, a pair of electron discharge devices each having electrodes including a grid and a cathode, a reactance in the cathode circuit of each of said devices, means for developing a voltage of carrier wave frequency to be modulated across the impedance between the grid and cathode of each device and the reactance in series therewith whereby currents of said frequency flow in said series circuits and phase displaced voltages of said frequency are developed between the grid and cathode of each device, means for varying the mutual conductance of said devices at signal frequency to thereby correspondingly vary the phases of said last voltages, and means for combining said last voltages in phase.

12. In a wave length modulator, an electron discharge device having electrodes including a grid and a cathode, a reactance, reactive at carrier wave frequency, in the cathode circuit of said device, means for developing a voltage of carrier wave frequency to be modulated across the impedance between said grid and cathode and said reactance in series whereby currents of said carrier frequency flow in said series circuit and a voltage of said carrier frequency and of a phase which is displaced relative to the phase of said first voltage is developed between said grid and cathode, means for varying the mutual conductance of said device at signal frequency to thereby correspondingly vary the phase of said last voltage, and frequency multiplying means cou-

pled to said grid and cathode for utilizing said phase varied voltage.

13. In a wave length modulation system, a pair of electron discharge devices each having electrodes including a grid and a cathode, an inductive reactance in the cathode circuit of one of said devices, a capacitive reactance in the cathode circuit of the other of said devices, means for developing a voltage of carrier wave frequency to be modulated across the impedance between the grid and cathode of each device and the reactance in series therewith whereby currents of said frequency flow in said series circuits and phase displaced voltages of said carrier frequency are developed between the grid and cathode of each device, means for varying the mutual conductance of said devices at signal frequency to thereby correspondingly vary the phases of said last voltages, and means for combining the said last voltages.

14. In a wave length modulation system, a pair of electron discharge devices each having electrodes including a grid and a cathode, an inductive reactance in the cathode circuit of one of said devices, a capacitive reactance in the cathode circuit of the other of said devices, means for developing in phase voltages of carrier wave frequency to be modulated across the impedance between the grid and cathode of each device and the reactance in series therewith whereby currents of said frequency flow in said series circuits and voltages oppositely displaced relative to the developed voltages of said carrier frequency appear between the grid and cathode of each device, means for varying the mutual conductance of said devices in phase opposed relation at signal frequency to thereby correspondingly vary the phases of said last voltages, and electron discharge tube means coupled to the grid and cathode of each device for combining the said phase varied voltages in phase or in phase opposition.

CHARLES N. KIMBALL.
